UNITED STATES PATENT OFFICE.

CHARLES HENRY ATKINS, OF SPRINGFIELD, MASSACHUSETTS.

STEAM-TRAP

1,216,394.

Specification of Letters Patent. Patented Feb. 20, 1917.

Application filed April 22, 1916. Serial No. 93,034.

To all whom it may concern:

Be it known that I, CHARLES HENRY ATKINS, a citizen of the United States of America, residing in the city of Springfield, 5 county of Hampden, and State of Massachusetts, have invented certain new and useful Improvements in Steam-Traps, of which the following is a specification.

This invention relates to improvements in 10 steam traps, particularly, it is designed for use in connection with drying rolls for drying cloth or paper. It is a well-known fact that steam, as it enters a closed body, cannot immediately heat the body until the confined air has become expelled.

The present invention is designed to readily permit the confined air to escape from the drying cylinder, whereby the steam will readily heat the cylinder and the drying 20 process be materially increased.

The invention, broadly, comprises an inclosed chamber having a sealed float mounted therein that normally closes the passage through which the water of condensation 25 escapes and yet permits the confined air in the drying cylinder to readily escape, it being understood that the interior of the drying cylinder is connected with the inclosing casing of the trap.

Referring to the drawings:

Figure 1 is a vertical sectional view through the trap showing the sealed float mounted therein and normally resting on the valve seat at the bottom of the inclosing casing, also showing the open ended hollow stem extending upward from the upper side of the float for permitting the confined air in the cylinder to pass from the inclosed casing into the interior of the stem 40 and downward through the float to the escape or return pipe;

Fig. 2 is a view of one of the bearings for supporting a drying cylinder and showing the manner of connecting the trap with the 45 interior of the cylinder;

Fig. 3 is a detail view of the lower end of the bushing adjacent the upper end of the sealed float.

Referring to the drawings in detail: 1 50 designates a portion of one of the drying cylinders, 2 the usual gear for rotating same, 3 the hollow bearing for rotatably supporting the drying cylinder, the hollow stem which enters the cylinder being understood 55 to pass through this bearing into the cylinder. 4 designates the inclosing casing of

the trap to which the short pipe 5 is connected, which in turn, leads to the common discharge pipe 6 to which a series of the traps are connected. 7 is a cap or cover 60 plate for closing the upper end of the casing 4. This plate is formed with a boss or bored out hub 8, the recess therein being indicated at 9. Located within this recess is a bearing 10 which may consist of bronze 65 or other suitable material. 11 designates the float proper which is a hermetically sealed ellipsoidal member having the continuous tube 12 extending therethrough, the opening through the tube being designated 70 by the numeral 13. The lower end of the tube is formed with a conical shaped valve 14 which normally engages the valve seat 15. The diameter of the opening 16 in the seat 15 is the same as the diameter of the 75 opening in the bearing 10. The upwardly extending hollow stem 17 that is located in the opening 18 is slightly smaller than the opening to permit the air which flows from the interior of the drying cylinder 1, 80 through the pipe 19, to the interior of the casing 4, to escape from the casing 4, the air passing upward through the annular passageway between the stem 17 and the opening 18 into the upper end of the boss 8 85 where it flows downward through the tube 12, as indicated by the arrow 20 and escapes by means of the pipes 5 and 6. After the air has been expelled from the drying cylinder 1, the steam then enters the interior of 90 the casing 4 and the water of condensation effectually seals the annular opening 18 against the escape of steam by reason of the water collecting in the grooves 21 of the stem 17, or, in other words, the capillary attraction between the grooves and the water serves to seal the tube 12 against the escape of the steam. After a sufficient quantity of water of condensation has collected in the bottom of the casing 4 the float 11 95 will be raised allowing the collected water to escape through the opening 16 past the valve 14. After the water has escaped the float again returns to its seat 15. Transversely arranged on the lower end of the bearing 10 are grooves 22 which communicate with the annular groove 23 at the lower end of the annular passageway 18. The grooves 22 and annular groove 23 are for the purpose of permitting the confined air 110 to pass upward through the opening 18 in case the float 11 is elevated, as it will be

seen the upper finished end or surface 23' of the float 11 cannot close the opening 18 by reason of this construction. The bearing 3 does not form a part of the present invention but is clearly shown, described and claimed in my co-pending application filed of even date herewith, entitled Hollow bolt construction, Ser. No. 93,085.

What I claim is:

- 10 1. A device of the class described, comprising in combination, an inclosing casing, a sealed float therein, a stem and a valve secured to the opposite ends of the float and in alinement with each other, a pipe extending through the float and connecting said stem and valve to provide a communicating opening with said stem and valve, the stem being located in a bearing that is slightly larger than the stem, the lower end of the bearing having an annular groove and a transverse groove in the lower end or face thereof extending from the outer edge of the bearing to the recess in the bearing, a pipe connected to the interior of the inclosing casing for introducing steam into said casing, said pipe being connected with the interior of a drying cylinder or roll, whereby when steam under pressure is turned on to the drying cylinder the confined air can readily escape from the cylinder through the pipe to the interior of the casing of the trap and then past the stem to and through the pipe which communicates with the stem and the valve, and whereby when the confined air has been expelled from the casing the water of condensation will seal the passageway between the stem and the bearing and cause the float to be lifted by the water of condensation in the casing and so escape past the valve to the discharge pipe, all constructed and arranged for the purpose described.
- 15 2. The herein described trap comprising an outer casing, or shell, having a discharge opening in the lower end of the casing, a cover plate formed with an integral recessed projection, a bearing in the recessed portion, a float within the casing, a valve on the lower end of the float for closing the discharge opening, the interior of said casing being free from obstruction or partitions of any kind, means for guiding the float to permit free upward and downward movements, said means comprising an extension on the float for entering the openings and recess in the shell and cover plate, respectively, the bearing having laterally arranged grooves communicating with the recessed bearing, the extension entering the opening in the cover plate being of less diameter than the opening in the cover plate and formed with grooves on said extensions to permit air but not water to pass along said extension, the upper end of the float having a flat surface for engaging the lower end of the bearing when the float is elevated, said

extensions having a communicating passageway from one to the other which leads through the float to allow air to pass from the interior of the casing to the discharge opening, and after the air has escaped from the casing and steam is admitted thereto, the grooves on the upper extension serving as a liquid seal to the passage through the float, whereby the float will be elevated by the water of condensation in the casing to raise the valve from and uncover the lower opening in the casing to permit the water of condensation to escape therefrom, and whereby the air in the casing can escape when the float is elevated and engages the lower end of the bearing.

3. A trap comprising an outer shell, having a pipe connection for introducing air or steam and having openings in its upper and lower portions, a closed float in the casing, a tube located within the float and having portions extending beyond its upper and lower ends, and located in said openings, the lower extending portion serving as a valve for the opening in the lower portion of the casing and the upper extension being of less diameter than the upper opening, having grooves therein to permit air to pass along said extension but not a liquid, the lower end of the upper opening having a groove therein to permit air to pass into the upper opening when the float is raised into contact with the lower end of the upper opening, as described.

4. A steam trap comprising an outer casing having a discharge opening at the bottom and a recessed cover plate, a float, a valve on the float to close the discharge opening, a grooved extension on the float located in the recess of the cover plate and of less diameter than the recess, the lower edge of the recessed opening having a groove to permit air to enter the recess when the float is elevated in contact with the lower edge of the recessed opening, said float having a communicating passage between the valve and the grooved extension to allow air to escape from the casing when the valve is closed, the grooved extension serving to seal the passage when steam is allowed to enter the casing, as described.

5. A device of the kind described, comprising in combination with an inclosing casing having an inlet opening in the side through which steam is allowed to enter the casing and a discharge opening in the bottom, a float in said casing, a cap for closing the upper end of the casing and formed with a recessed projection, a bearing or lining in the recess of the projection and formed with an annular groove at its lower end and transverse grooves extending from the edge of the flange to the annular groove, said float having its upper end finished to contact with the lower end of the grooved

flanged bearing, projections on the upper and lower ends of the float for entering the bearing in said projection and the discharge opening in the lower end of the casing for the purpose of guiding the vertical movements of the float, the lower projection serving as a valve for the discharge opening, a pipe extending through the float for forming a communication between the projec-

tions, said grooves serving to permit the air 10 confined in the casing to escape therefrom to and through the float should the float be in an elevated position when the steam is turned on, as described.
